United States Patent Office

Des. 184,048
Patented Dec. 9, 1958

184,048

COMPUTER CONSOLE

Walter Furlani, Endicott, and William H. Harkins, Vestal, N. Y., assignors to International Business Machines Corporation, New York, N. Y., a corporation of New York

Application December 12, 1957, Serial No. 48,878

Term of patent 14 years

(Cl. D26—5)

FIG. 1.

FIG. 2.

Fig. 1 is a front perspective view of a computer console showing our new design;

Fig. 2 is a rear elevation of the same.

The right side of the computer console is plain.

Portions of Fig. 1 are diagonally lined to indicate transparency.

We claim:

The ornamental design for a computer console, as shown and described.
